UNITED STATES PATENT OFFICE

CORINNE MOONEY, OF MEMPHIS, TENNESSEE

DESIGN FOR A MAIL BOX

Application filed September 21, 1931. Serial No. 41,163. Term of patent 3½ years.

To all whom it may concern:

Be it known that I, CORINNE MOONEY, a citizen of the United States of America, residing at Memphis, in the county of Shelby and State of Tennessee, have invented a new, original, and ornamental Design for a Mail Box, of which the following is a specification, reference being had to the accompanying drawings, forming a part hereof.

In the drawings:

I claim:

The ornamental design for a mail box, as shown.

CORINNE MOONEY.
